COMBINED TENNIS RACKET AND BALL CARRYING CASE

Patrick E. Haggerty, Jr., 3411 E. Kiest Blvd.,
Dallas, Tex. 75203

Filed May 30, 1975, Ser. No. 582,107

Term of patent 3½ years

Int. Cl. D3—02

U.S. Cl. D87—1 R

FIG. 1 FIG. 2 FIG. 3 FIG. 4

FIG. 5 FIG. 6

FIG. 1 is a front elevational view of a combined tennis racket and ball carrying case showing my new design;

FIG. 2 is a rear elevational view;

FIG. 3 is a left side elevational view;

FIG. 4 is a right side elevational view;

FIG. 5 is reduced scale perspective view thereof in an open position; and

FIG. 6 is a top plan view thereof.

I claim:

The ornamental design for a combined tennis racket and ball carrying case, substantially as shown and described.
